UNITED STATES PATENT OFFICE.

PATRICK T. DEMPSEY, OF BOSTON, MASSACHUSETTS.

SLEEVE PROTECTOR.

Application filed April 12, 1926. Serial No. 101,317.

This invention relates to a sleeve protector, and more particularly to such a protector as might be used by machinists, or 5 automobilists who find it necessary to make repairs or adjustments to their automobiles when on the road, at times when it is not advisable to remove their outer coats or jackets when such repairs or adjustments are to be made.

10 It is an object of the invention to produce a simple, inexpensive and durable sleeve protector capable of protecting the shirt sleeves of the wearer, or the sleeves of his jacket or even the sleeves of an outer 15 coat in the event that one is being worn, and which will in each instance snugly and comfortably surround the sleeve and present a neat and well fitted appearance with no 20 gaping, ballooning or slack portions to hamper the wearer by being caught by projecting portions of the machine or engine upon which he may be at work.

Other objects of the invention will be 25 fully understood from a description of the drawing and the claims hereinafter given.

Of the drawing,

Figure 1 represents the improved sleeve protector as applied for use.

Figures 2 to 5 inclusive are sections taken 30 on the line X—X Figure 1 showing the various adjustments which might be made to accommodate the sleeve with which the protector is to be used, hatching being left out for clearness.

35 Figure 6 is a detail to be referred to.

Like characters represent like parts throughout the several figures of the drawing.

Referring to the drawing,

40 The drawing herewith illustrates a sleeve protector wherein the body portion 10 is or may be made of leather or other suitable material but preferably of a pliable material which will normally hold its shape yet susceptible to easy manipulation for the purpose of adjustment to accommodate the size or bulk of sleeve which it may be required to cover.

45 It is an object of the invention to produce a sleeve protector which may be rapidly adjusted for use whether the intended wearer is in shirt sleeves, wearing a jacket or a heavy coat, and when adjusted for use shall be of snug but comfortable fit to prevent 50 gaping at the upper portion to eliminate the

possibility of its catching on projecting objects adjacent the work at hand.

Attached to the body portion 10 is a wrist band 11 which has a plurality of snap fastener members 12 to the number required which are arranged to engage other fastening members 12^x at different times for the extent of adjustment desired, so that the said band may be snugly fitted to the wrist of a large as well as a small person.

55 Figures 1, 2 and 4 of the drawing show the protector in an adjusted position which might be assumed when it is covering the sleeve or cuff of a jacket, and which might be said to be an intermediate adjusted position assuming that when applied to shirt sleeves it is adjusted to one extreme position, and when applied to a heavy outer coat it is in another extreme position.

60 Viewing Figures 1 and 2 it will be seen that there is a row of snap fastener members 13 outside the protector body 10 adjacent the edge 15, and another row 16 further removed from the said edge, each of which is arranged to be engaged by a row of fastener members 17 arranged on the inside of the body 10 adjacent the edge 18 thereof, the said figures showing the row 13 engaged by the row 17 which arrangement might be a convenient one to use when the protector is covering a jacket sleeve while the row 16 might be engaged with the row 17 when the protector covers a shirt sleeve.

65 Figure 4 of the drawing shows the fastener members 17 as engaged with another row of fastener members 19 which are located on the inside of the protector body adjacent the edge 15 which arrangement is a very convenient one as the action of uniting the two parts of the fasteners while in that 70 position is a very easy one to accomplish.

75 In the event that the protector is to be used to cover the sleeves of a heavy outer coat, provision is made to do so by bringing into use the flap 20, one edge of which is 80 stitched to the inside of the body 10 at 21 along the edge 18 of said body, its other edge 22 and the two ends 23 and 24 being 85 free.

90 Adjacent the edge 22 is a row of snap fastener members 25 equal in number to the rows 13 and 19 with either of which rows the said members 25 may be engaged as conditions warrant, and as seen in Figures 3 95 and 5 of the drawing.

When out of use the flap 20 will automatically assume the position shown in Figures 2 and 4 of the drawing.

Viewing Figure 1 it will be seen that the body 10 is quite full and tapering slightly toward the wrist band and just before reaching which it quite suddenly narrows in but leaving considerable fullness at the point where the jacket or coat sleeve might be expected to end so that when the protector is secured in place the jacket or coat sleeve will not be so compressed or crimped as to cause a feeling of uneasiness and discomfit to the wearer.

As an aid to prevent the jacket or coat sleeve from working out of the protector or to prevent the upper end of the protector from working toward the wrist of the wearer, I provide a clamp member 30 at the end of a cord 31, the said clamp being arranged to be engaged with the sleeve at a point above the protector to thus retain the two in adjusted position.

Having described the invention I claim.

1. A sleeve protector of the class described comprising a body portion, and a wrist portion, each of said portions being arranged to be wrapped about the forearm of a person, and having edges which may overlap, said body portion being provided with a plurality of fastening members arranged in a row adjacent to and parallel with one edge thereof, and a plurality of other fastening members arranged in a row and removed an appreciable distance from and parallel with said edge; a flap having one of its longitudinal edges secured to another edge of said body portion, said flap being normally concealed inside said body portion and having a plurality of fastening members in a row on

one face thereof and adjacent the edge to which it is stitched and arranged to engage either of the two first mentioned rows of fastener members, and having a row of fastening members on another face adjacent the free longitudinal edge thereof, and also arranged to engage either of the two first mentioned rows of fastening members for the purpose of adjustably securing said protector to a person; and means to adjust the said wrist portion to suit the wearer.

2. A sleeve protector of the class described comprising a body portion and a wrist portion each of said portions being arranged to be wrapped about the forearm of a person, and having longitudinal edges which may overlap, said body portion being provided with a plurality of fastening means arranged in two rows on the outer face of said body portion, one of said rows being adjacent to and parallel with one edge of said portion, and the other row removed from but parallel with said first row; said portion having a plurality of fastening members on the inner face thereof and adjacent the said edge; a flap having one of its longitudinal edges secured to another edge of said body portion and having a plurality of fastening members on one face thereof adjacent said other edge and a plurality of fastening members in a row on its other face adjacent the free edge of said flap, said first three rows of fastening members being engageable by either of the rows of said flap whereby various adjustments in the body portion may be made; and means to adjust the said wrist portion to suit the wearer.

Signed by me at Boston, Massachusetts this 7th day of April, 1926.

PATRICK T. DEMPSEY.
